INVENTOR:

Louis S. Ullman

UNITED STATES PATENT OFFICE.

LOUIS S. ULLMAN, OF NASHVILLE, TENNESSEE.

HYGROMETER.

Specification of Letters Patent No. 25,457, dated September 13, 1859.

To all whom it may concern:

Be it known that I, LOUIS S. ULLMAN, of Nashville, in the county of Davidson and State of Tennessee, have invented a new and 5 Improved Hygrometer, which I term the "Oriental and Occidental Weather-Indicator;" and I do hereby declare that the following is a full, clear, and exact description of the same, reference being had to the accompanying drawings, forming part of this 10 specification, in which—

Figure 1 is a front view. Fig. 2 is a central section. Fig. 3 is a view of the capsule and tail-like appendage of the Arabian 15 plant known as "chahajin" or "chahân" constituting the principal portion of the instrument, and represented in the natural condition.

Similar letters of reference indicate corresponding parts in the several figures.

Certain plants, as the "chahajin" or "chahân" of Arabia represented in the accompanying drawing, and the "Geranium erodium" well known in this country and 25 in Europe, have attached to their capsules a tail-like appendage, part of which is naturally of a spiral form, and tends to unwind itself, or wind itself up as the atmosphere in which it is exposed becomes more or less 30 moist.

My invention consists in the construction of a hygrometer of convenient form by combining an index, or its equivalent, and a graduated dial or scale in any manner, substantially as hereinafter described, with the capsule and spiral tail-like appendage of the above specified plants.

The drawing represents the most convenient form of my improved hygrometer and 40 after describing that form a few remarks will suffice to explain the other form that may be adopted.

A, is a box which may be of brass, or other metal, wood or other substance, made 45 with a solid back a, but with a movable glazed front B, around the interior of which is an open dial plate or ring b, graduated in any suitable or convenient manner. This box must have one or more suitable 50 openings j, in the sides or other part for the admission of air.

c d e, is the sensitive portion of the hygrometer; c, being the capsule; d, the spiral portion of its tail-like appendage, and e,

the extreme portion of the said appendage 55 which is not twisted. The portion e, is firmly secured by wax or cement or by any other means to the back a, of the box, in such a manner that the capsule, and the spiral portion project forward in the center 60 of the box perpendicularly to the sides and front thereof.

f, is the index having a hole in its center which fits tightly on the capsule c.

g, is a small collet secured to a frame 65 upon the glass h, of the front of the box to receive the front extremity of the capsule and prevent its lateral displacement. This collet is large enough for the capsule to work freely within it.

i, is a plate secured to the interior of the back of the box for the purpose of covering up the portion e, and giving a finished appearance to the interior of the instrument.

As the spiral portion d, of the plant winds 75 up, or unwinds itself with the changes in the hygrometric condition of the atmosphere the capsule c, having the index attached is caused to turn back and forth, and if the dial is properly graduated the index 80 will indicate the degree of moisture in the atmosphere, and so foretell changes of weather. The dial, besides being graduated, or instead of being graduated, may be marked in any manner that will be best 85 understood for the purpose of indicating the changes of weather.

Instead of attaching an index to the capsule to indicate upon a dial or circular scale, a small weight may be suspended 90 from a thread which is attached to, and wound around the capsule, and the said weight having a vertical scale arranged near it will ascend and descend the said scale as its suspending thread is wound up or unwound by the action of the spiral portion d, upon the capsule c. The suspended weight 95 may work within a glass tube having a properly graduated scale placed at the back of it. The suspended weight is an equivalent for the index f, and the vertical scale 100 the equivalent for the dial or circular scale b.

I do not claim the combination of an index with a vegetable substance twisted by 105 art. Neither do I claim the use of the naturally spiral portions of plants when not applied, as I have described, in combination

with dials and indices or their equivalents. But

What I claim as my invention, and desire to secure by Letters Patent, is:—

5 The combination of the capsule and naturally spiral tail-like appendage of either of the plants herein specified with an

index and dial, or their equivalents, substantially as herein described to constitute a hygrometer.

LOUIS S. ULLMAN.
